COMBINED GRILLE AND LAMP UNIT FOR AN AUTOMOBILE

John R. Dickerson, Pontiac, Mich., assignor to Chrysler
Corporation, Highland Park, Mich., a corporation of
Delaware

Filed May 2, 1960, Ser. No. 60,413

Term of patent 7 years

(Cl. D14—18)

Fig. 1 is a front elevational view of a combined grille and lamp unit for an automobile showing my new design;
Fig. 2 is a top plan view thereof;
Fig. 3 is a side elevational view;

Fig. 4 is a sectional view taken on the line 4—4 of Fig. 1;

Figs. 5 and 6 are fragmentary sectional views taken on the lines 5—5 and 6—6, respectively, of Fig. 4; and

Fig. 7 is a fragmentary sectional view taken on the line 7—7 of Fig. 1.

The dominant features of my design reside in the full line portions of the drawings.

I claim:

The ornamental design for a combined grille and lamp unit for an automobile, substantially as shown and described.
